UNITED STATES PATENT OFFICE.

CASTEN IVAN TISELL, OF STOCKHOLM, SWEDEN.

EXPLOSIVE AND PROCESS FOR MANUFACTURING IT.

1,393,984.

Specification of Letters Patent.

Patented Oct. 18, 1921.

No Drawing.

Application filed July 23, 1918. Serial No. 246,392.

To all whom it may concern:

Be it known that I, CASTEN IVAN TISELL, a subject of the King of Sweden, residing in Kungsgatan 72, Stockholm, in the Kingdom 5 of Sweden, have invented certain new and useful Improvements in Explosives and Processes for Manufacturing Them, (for which I have filed application in Sweden May 18, 1917; Germany, May 15, 1918; Denmark, May 17, 1918, and Norway, May 16, 10, 1918,) of which the following is a specification.

It is known how to manufacture co-called safety explosives, containing nitro-hydro-carbons, ammonium perchlorate or similar substances which give off oxygen, as well as aluminium powder, with or without admixture of wood-meal, pulverized carbon or other substances. The object of the admixture 15 of aluminium powder in these explosives is to increase the temperature of the explosion and thereby to increase the effect of the explosive.

These explosives are however not quite 20 stable, inasmuch as the aluminium powder becomes oxidized during the storage of the explosive for some length of time. This drawback is eliminated entirely, or is essentially diminished according to the present 25 invention whereby part of the aluminium is replaced by ferro-silicon with a high percentage of silicon, suitably 90 to 95% Si, so that the explosive, together with the aluminium powder will contain ferro-silicon 30 with a high percentage of silicon. Hereby 35 is also attained the advantage that, owing to the higher combustion heat of the aluminium, the heat evolved in the combustion will be transferred more rapidly to the explosion 40 gases and will impart a higher temperature to the latter than if ferro-silicon solely were to be employed instead of aluminium.

The following may serve as an example 45 of the composition of an explosive in accordance with the present invention:

2-3 parts by weight of aluminium powder,

6-9 parts by weight of high per cent. 50 ferro-silicon,

8-13 parts by weight of wood meal, pulverized carbon, pulverized cellulose, or the like,

10-15 parts by weight of mono-, di-, or 55 trinitro benzol, or else solid or liquid mono-, di- or trinitro toluol,

60-80 parts by weight of ammonium perchlorate.

In lieu of the above mentioned nitro-hydro-carbons, other nitro-hydro-carbons 60 may be used. If liquid nitro-hydro-carbons are employed, they may suitably be gelatinized to the desired degree with nitro-cellulose, also some collodion, e. g. 3-5 parts by weight may be added. In order to neutralize chlorin or hydro-chloric acid released in the explosion, which is of great importance in underground blasting, e. g. in mines or tunnels, an equivalent quantity of alkali-metal nitrate, e. g. nitrate of sodium or nitrate of the alkaline earth metals, such as nitrate of barium or strontium, may be added, whereby the chlorin which would otherwise be released is combined with the alkali-metal or with the alkaline earth metal. 75

The following may serve as an example of the composition of such an explosive:

2-3 parts by weight of aluminium powder, 70
6-9 parts by weight of high per cent. ferro-silicon,

8-13 parts by weight of wood powder, pulverized carbon, pulverized cellulose or the like,

8-15 parts by weight of mono-, di-, or trinitro benzol, or else mono-, di-, or tri-nitrotoluol, 85

25-35 parts by weight of sodium nitrate or nitrate of barium or strontium,

35-55 parts by weight of ammonium perchlorate, 90

2-15 parts by weight of paraffin, wax, or similar substance.

The paraffin is added to the mixture suitably in a melted state, whereby the advantage of a more intimate mixture is attained. 95

Having thus described my invention I declare that what I claim is:—

1. A safety explosive of the class described containing nitro-hydrocarbons, oxygen yielding substances, combustible carbonaceous substances, aluminium-powder and ferro-silicon containing 90 to 95% of silicon. 100

2. A safety explosive of the class described containing nitro-hydrocarbons, ammonium perchlorate, combustible carbonaceous substances, aluminium-powder and ferro-silicon containing 90 to 95% of silicon. 105

3. A safety explosive of the class described containing nitro-hydrocarbons, perchlorates and nitrates, combustible carbonaceous substances, aluminium-powder and ferro-silicon containing 90 to 95% of silicon. 110

4. An explosive of the class described, containing 2-3 parts by weight of aluminum powder, 6-9 parts by weight of ferro-silicon containing 90 to 95% of silicon, 8-13 parts by weight of a combustible carbonaceous substance, 10-15 parts by weight of a nitro-derivative of benzol, 60-80 parts by weight of ammonium perchlorate.
5. An explosive of the class described, 10 containing 2-3 parts by weight of aluminum powder, 6-9 parts by weight of ferro-silicon containing 90 to 95% of silicon, 8-13 parts by weight of a combustible carbonaceous substance, 10-15 parts by weight of a nitro-derivative of benzol, 60-80 parts by weight of ammonium perchlorate.

con, 8-13 parts by weight of a combustible carbonaceous substance, 10-15 parts by weight of a nitro-derivative of benzol, 60-80 15 parts by weight of ammonium perchlorate, and 2-15 parts by weight of paraffin.

In witness whereof I have hereunto set my hand in presence of two witnesses.

CASTEN IVAN TISELL.
